UNITED STATES PATENT OFFICE.

DRIKUS SNITZER AND MICHAEL KUEHN, OF ST. LOUIS, MISSOURI.

TAKE-UP FOR SEWING-MACHINES.

SPECIFICATION forming part of Letters Patent No. 485,019, dated October 25, 1892.

Application filed February 16, 1892. Serial No. 421,728. (Model.)

To all whom it may concern:

Be it known that we, DRIKUS SNITZER and MICHAEL KUEHN, citizens of the United States, residing at St. Louis, State of Missouri, have 5 invented certain new and useful Improvements in Take-Ups for Sewing-Machines, of which the following is a specification, reference being had therein to the accompanying drawings.

10 Our invention relates to that class of take-up devices for sewing-machines in which a rotary take-up in the head of the machine is operated in such a manner as to have a differential or variable rotary movement for the 15 purpose of properly controlling the thread with reference to the movements of the needle.

In carrying our invention into effect we mount our rotary take-up on a small shaft properly journaled in the head of the machine, said shaft being provided with an operating-arm, with which a pin connected with a pitman which operates the needle-bar has a loose connection in such a manner as to impart a differential rotary movement to the 25 take-up shaft. This pin which operates the take-up shaft is preferably carried by an arm attached to a block which is rigid with the needle-bar pitman, so that the rocking movements of the said pitman will be imparted to 30 the said arm, thus causing the pin carried by the latter and which is eccentric to the crank-pin which operates the pitman to travel in an elliptical path, and thereby impart an irregular or variable movement to the take-up shaft.

35 In the accompanying drawings, Figure 1 is a front view of the head of a sewing-machine provided with our improved take-up mechanism. Fig. 2 is a sectional elevation of the same, and Fig. 3 is a detail sectional view on line 3 3, Fig. 2. Fig. 4 is a sectional elevation similar to Fig. 2, showing a slightly-modified form of our invention.

A denotes the head at the forward end of the bracket-arm of a sewing-machine, and B 45 the usual driving-shaft, journaled in the upper part of the arm and provided with a crank b, the crank-pin b' of which is connected by a pitman C with the block d, attached to the needle-bar D. Rigid with the pitman C is a 50 block e, provided with an arm or portion d', to which is rigidly attached the take-up arm E, provided at its upper end with a pin e.

F denotes the rotary take-up, carried by a small shaft f', journaled in a hanger or bracket a, attached to or formed integral with the 55 head A and provided with a slotted operating-arm f, which is engaged by the pin e of the arm E, said pin e being, as shown in Figs. 1 and 2, out of line with or eccentric to the crank-pin b'. 60

With the parts constructed as above described it will be apparent that when the shaft B is set in motion the pitman C will be caused to operate the needle-bar in the usual manner, and as the said pitman in its movements is caused to sway or vibrate as it is operated by its crank-pin the pin e, carried by the arm E, which is rigid with the pitman C, will be caused to describe an elliptical path, and will therefore move in and 70 out in the slot of the arm f of the take-up shaft, and will thus impart a variable rotary movement to the take-up, the said pin e being at the inner portion of the slot of the arm f at the moment when the take-up is to operate 75 to tighten the loops of needle-thread, thereby imparting a quick rotary motion to the take-up, the said pin e being farther outward in the slot of the arm of the take-up shaft during the time when the needle is descending 80 and when the thread is to be gradually slackened.

Instead of forming the loose connection between the arm f of the take-up shaft and the pin e by slotting the said arm, the same operative result may be effected by connecting the pin e with the said arm by means of a short link, thereby differentially rotating the take-up in a manner like the connection effected by means of the slotted arm above described. 85 90

The take-up shaft f' is shown in Figs. 1 and 2 as being so arranged that its axis is in line with the axis of the driving-shaft B; but, owing to the manner in which we operate said 95 take-up shaft from the pin e, connected with the needle-bar-operating pitman in such a manner as to travel in an elliptical path, we are enabled to secure a proper differential rotary movement of the take-up with the parts 100 so arranged. The take-up may, however, be so arranged that its axis is somewhat out of line from the axis of the driving-shaft, as shown in Fig. 4, and in such case, with the

pin *e* carried and operated as shown, the differential movements of the rotary take-up will be somewhat increased, so that it will move more quickly at the moments when the 5 stitches are tightened than with the construction shown in Figs. 1 and 2. It is, however, necessary in actuating a rotary take-up from the needle-bar-operating pitman that the axis of the take-up shaft should not be far removed from the axis of the driving-shaft, as would be the case were the take-up merely a vibrating one, such as are shown by the take-ups of United States Patents Nos. 399,949 and 420,034, it being, in our opinion, essential, in 10 order to operate the rotary take-up from a device rigid with the needle-bar pitman, that the axis of the take-up shaft should be in line with the axis of the needle-operating shaft, or approximately so, as herein shown 15 and described.

Having thus described our invention, we claim and desire to secure by Letters Patent—

1. A sewing-machine take-up mechanism consisting of the combination, with a rotating 25 driving-shaft provided with a crank, of a needle-bar, a pitman serving to connect said needle-bar with said crank, a rotary take-up, a shaft by which said take-up is carried and which is provided with an operating-arm, the 30 axis of the said take-up shaft being in line with the axis of said driving-shaft, or approximately so, as shown and described, and a pin operated from said pitman and having a loose connection with the arm of said take-up shaft, and thereby serving to impart a differential 35 rotary motion to said take-up.

2. A sewing-machine take-up mechanism consisting of the combination, with a rotating driving-shaft provided with a crank, of a 40 needle-bar, a pitman serving to connect said needle-bar with said crank, a rotary take-up, a shaft by which said take-up is carried and which is provided with a slotted operating-arm, the axis of the said take-up shaft being

in line with the axis of said driving-shaft, or 45 approximately so, as shown and described, and a pin operated from said pitman and engaging the said slotted arm of said take-up shaft, and thereby serving to impart a differential rotary motion to said take-up. 50

3. A sewing-machine take-up mechanism consisting of the combination, with a rotating driving-shaft provided with a crank, of a needle-bar, a pitman serving to connect said needle-bar with said crank, a rotary take-up, 55 a shaft by which said take-up is carried and which is provided with an operating-arm, the axis of the said take-up shaft being in line with the axis of said driving-shaft, or approximately so, an arm rigidly attached at its lower 60 end to the lower end of said pitman and provided at its upper end with a pin having a loose connection with the said arm of the take-up shaft.

4. A sewing-machine take-up mechanism 65 consisting of the combination, with a rotating driving-shaft provided with a crank, of a needle-bar, a pitman serving to connect said needle-bar with said crank, a rotary take-up, a shaft by which said take-up is carried and 70 which is provided with a slotted operating-arm, the axis of said take-up shaft being in line with the axis of said driving-shaft, or approximately so, an arm rigidly attached at its lower end to the lower end of said pitman 75 and provided at its upper end with a pin engaging the said slotted arm of the take-up shaft.

In testimony whereof we affix our signatures in presence of two witnesses.
